Primary Examiner — Susan Bennett Hattan*Assistant Examiner* — Suzanne E Tisdell(74) *Attorney, Agent, or Firm* — Reising Ethington P.C.(57) **CLAIM**

The ornamental design for a vehicle grille, as shown and described.

DESCRIPTION

FIG. 1 is a perspective view of the vehicle grille;

FIG. 2 is a front view thereof;

FIG. 3 is a left side view thereof (where the right side view is substantially a mirror image of the left side view); and, FIG. 4 is a top view thereof.

In the drawings, the broken lines depict portions of the vehicle grille that form no part of the claimed design.
